(57) **CLAIM**

The ornamental design for a lateral adapter for biopsy system as shown and described.

DESCRIPTION

FIG. 1 is a top perspective view of a first example of a lateral adapter for biopsy system in an environment.

FIG. 2 is a top perspective view of the lateral adapter for biopsy system of FIG. 1.

FIG. 3 is a bottom perspective view of the lateral adapter for biopsy system of FIG. 1.

FIG. 4 is a front view of the lateral adapter for biopsy system of FIG. 1.

FIG. 5 is a back view of the lateral adapter for biopsy system of FIG. 1.

FIG. 6 is a right side view of the lateral adapter for biopsy system of FIG. 1.

FIG. 7 is a left side view of the lateral adapter for biopsy system of FIG. 1.

FIG. 8 is a top view of the lateral adapter for biopsy system of FIG. 1; and,

FIG. 9 is a bottom view of the lateral adapter for biopsy system of FIG. 1.

The broken lines depict an environment or portions of the lateral adapter for biopsy system that form no part of the claimed design.
